(57) **CLAIM**

The ornamental design of a cupholder tray, as shown.

DESCRIPTION

FIG. 1 is a side perspective view of the cupholder tray showing my new design;

FIG. 2 is a top plan view thereof;

FIG. 3 is a bottom plan view thereof;

FIG. 4 is a right side elevational view of the cupholder tray as shown in FIG. 3;

FIG. 5 is a left side elevational view of the cupholder tray as shown in FIG. 3;

FIG. 6 is a left side elevational view of the cupholder tray as shown in FIG. 1; and,

FIG. 7 is a right side elevational view of the cupholder tray as shown in FIG. 1.

The broken line showing of a cupholder receptacle is included for the purpose of illustration only and forms no part of the claimed design.

1 Claim, 6 Drawing Sheets
